UNITED STATES PATENT OFFICE.

ERNEST F. MUDD AND TOBY SEVERESE, OF WASHINGTON, DISTRICT OF COLUMBIA.

CUTTING-TABLE.

1,119,107.

Specification of Letters Patent.

Patented Dec. 1, 1914.

Application filed July 1, 1913. Serial No. 776,791.

To all whom it may concern:

Be it known that we, ERNEST F. MUDD and TOBY SEVERESE, citizens of the United States of America, residing at Washington, 5 in the District of Columbia, have invented certain new and useful Improvements in Cutting-Tables, of which the following is a specification.

This invention relates to cutting tables, 10 and particularly to tables designed for use by tailors in cutting patterns from stock paper; and it has for its primary object the provision of a device of this character which will embody means for respectively 15 supporting the pattern paper and cloth and for permitting the same to be extended superimposed relatively over the top of the table and arranged thereon so that the pattern may be readily formed on the paper.

20 Another object of the invention is the provision of a device of this character for supporting the paper in ordinary roll and stock form.

Another object of the invention is to provide means for facilitating the operation of rewinding the cloth onto its receiving roll after the cutting operation.

Another object of the invention is the provision of means for holding the cloth 30 against rewinding movements during the pattern forming operation.

With these and other objects in view, the invention consists of certain novel features of construction, combination and arrangement of parts, as will be hereinafter described and claimed.

In the accompanying drawings:—Figure 1 is a perspective view of the table, showing the method of extending the cloth and 40 paper thereover; Fig. 2 is a longitudinal section through a portion of the table, showing the paper and cloth arranged superimposed relatively over the top of the table; and Fig. 3 is a section through a portion of 45 the cloth supporting roll.

The table 1 herein conventionally illustrated is provided at one end with superimposed series of brackets 2, the same being arranged in mating pairs and provided respectively with openings and slots 3 and 4 for a purpose to be hereinafter referred to. The brackets 2 are secured by means of suitable fastenings 5 to the legs 6 of the table and arranged preferably adjacent the top 7 of the table and at one end thereof. At a point immediately above the brackets the

adjacent end of the top 7 is provided with a surface 8 which is gradually curved onto the upper flat surface of the top 7, as shown, and it is designed to form a guide to permit 60 the cloth and the paper to be readily drawn over the top and arranged in a flat condition upon the surface 9 thereof.

The brackets 2 of the lower series hereinbefore described removably support a roll 10 on which is wound the pattern paper 11. The brackets of the upper series removably support a roll 12 on which the pad forming cloth 13 is wound. The upper roll 12 is provided at one end with a trunnion 14 70 mounted to revolve in the passage 3 of the adjacent bracket 2 while at the opposite end the roll is provided with a rectangular trunnion 15 which is fitted in the recess 4 in the other bracket 2. The trunnion 15 is connected permanently to the roll 12, as at 15 and operatively connected with the roll and with the trunnion is a spring 16 which serves to normally hold the roll under tension and thereby retain the cloth 13 in a 80 wound condition. The roll 12 is provided with a suitable ratchet detent 17, whereby the cloth may be held against rewinding upon the roll after the same has been extended over the surface 9 of the table top 85 7. From this construction it is obviously seen that the free ends of the materials 11 and 13 may be grasped in the hands of the operator as shown in Fig. 2, and extended over the surface 9 and arranged superimposed thereon and the paper exposed so that the pattern may be readily formed thereon. The arrangement is such as will expedite 90 the operation of arranging the cloth and the paper in proper relative positions and for holding the same against separation from one another during the cutting operation. After the cutting operation the under pad forming cloth may be drawn upwardly and outwardly so as to affect the ratchet detent 95 and permit the cloth to be automatically wound onto the roll 12, under the action of the spring 16. It will be observed that through the relative arrangement of the two rolls referred to the pattern paper when 100 arranged in the position shown in Fig. 2 will extend over the space between both rolls, whereby to permit of a knife or pair of scissors or the like to be extended into said space and manipulated to sever that 105 portion of the pattern which overlies the table top from that portion of the paper 110

that remains on the roll. This may be done expeditiously and without possibility of injuring the backing cloth as will be understood.

5 From the foregoing description, taken in connection with the accompanying drawings, the construction and operation of the invention will be readily understood without requiring a more extended explanation.

10 Various changes in the form, proportion and the minor details of construction may be resorted to without departing from the principle or sacrificing any of the advantages of this invention as claimed.

15 Having thus described our invention, what we claim is:—

A tailor's pattern cutting table provided with a top having one transverse curved edge merging onto the upper flat surface a 20 pair of brackets secured to the end of said

table, a removably mounted roll in said brackets to receive the pattern paper, a pair of brackets mounted above the first mentioned pair of brackets, a revolvably mounted spring actuated roll removably supported 25 in said brackets, on which is wound the pad forming cloth, and spaced longitudinally from the first mentioned roll throughout its length, so that the pattern paper may be extended upwardly against one side of 30 the backing cloth supporting roll and over the space between both rolls.

In testimony whereof we affix our signatures in presence of two witnesses.

ERNEST F. MUDD.
TOBY SEVERESE.
